(57) **CLAIM**

The ornamental design for a vanity, as shown and described.

DESCRIPTION

FIG. 1 is a front perspective view of a vanity according to the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of section 8 of FIG. 4 showing the left side view of a handle; all of the handles in the drawings have the same left side view with the right side views being mirror images thereof.

(Continued)

Portions of the vanity shown in broken lines are not part of the claimed design. The bold broken lines in FIG. 4 and FIG. 8 depict the boundaries of the enlarged views that form no part of the claimed design.

1 Claim, 4 Drawing Sheets
